(57) **CLAIM**

The ornamental design for an illuminated rub rail, as shown and described.

DESCRIPTION

FIG. 1 is a head on frontal view of a illuminated rub rail;

FIG. 2 is a cross-sectional side view of the illuminated rub rail of FIG. 1, taken along line 2—2 of FIG. 1; and,

FIG. 3 is a perspective view of the illuminated rub rail of FIG. 1.

The broken lines shown along the left and right sides of the illuminated rub rail of FIGS. 1 and 3 represent the bounds of the claimed design while all other broken lines are directed to environment and are for illustrative purposes only; the broken lines form no part of the claimed design.

1 Claim, 3 Drawing Sheets
